Patented Jan. 29, 1974

230,191

ONE PASS COMBINATION WOOD HOGGING AND PULVERIZING MACHINE

Harry D. Schutte, Williamsville, N.Y., assignor to Schutte
Pulverizer Co., Inc., Buffalo, N.Y.

Filed May 5, 1972, Ser. No. 250,862

Term of patent 14 years

Int. Cl. D15—09

U.S. Cl. D55—1 B

Fig. 4

Fig. 5.

FIG. 1 is a front elevational view of the wood hogging and pulverizing machine;

FIG. 2 is a rear elevational view thereof;

FIG. 3 is a top plan view thereof; and

FIGS. 4 and 5 are end elevational views thereof.

I claim:

The ornamental design for a one pass combination wood hogging and pulverizing machine, as shown and described.
